Primary Examiner — Sheryl Lane*Assistant Examiner* — Nicole C Shiflet(74) *Attorney, Agent, or Firm* — Akerman LLP**CLAIM**

The ornamental design for a grill base, as shown and described.

DESCRIPTION

FIG. 1 is a perspective view of the “grill base” showing my new design;

FIG. 2 is a bottom perspective view of the embodiment of FIG. 1;

FIG. 3 is a front view of the embodiment of FIG. 1;

FIG. 4 is a back view of the embodiment of FIG. 1;

FIG. 5 is a right side view of the embodiment of FIG. 1;

FIG. 6 is a left side view of the embodiment of FIG. 1;

FIG. 7 is a top view of the embodiment of FIG. 1;

FIG. 8 is a bottom view of the embodiment of FIG. 1;

FIG. 9 is a perspective view of a second embodiment of the “grill base”;

FIG. 10 is a bottom perspective view of the embodiment of FIG. 9;

FIG. 11 is a front view of the embodiment of FIG. 9;

FIG. 12 is a back view of the embodiment of FIG. 9;

FIG. 13 is a right side view of the embodiment of FIG. 9;

FIG. 14 is a left side view of the embodiment of FIG. 9;

FIG. 15 is a top view of the embodiment of FIG. 9; and,

FIG. 16 is a bottom view of the embodiment of FIG. 9.

The broken lines showing portions of the article and environment form no part of the claimed design.
